UNITED STATES PATENT OFFICE

LEO EDELMANN, OF CHICAGO, ILLINOIS, ASSIGNOR TO E. EDELMANN & CO., OF CHICAGO, ILLINOIS, A CORPORATION OF ILLINOIS

SYRINGE HYDROMETER

Application filed July 17, 1925. Serial No. 44,306.

This invention relates to syringe hydrometers, and particularly to a hydrometer of this character having a glass or other frangible barrel containing the float.

5 An object of this invention is to provide a syringe hydrometer of few parts and which can be readily assembled.

Another object is to so construct the hydrometer that the frangible portions are 10 protected against breakage through dropping or other shocks encountered in use.

With these and other objects in view which will be apparent to those skilled in the art, this invention embraces novel features of construction and combination of parts which will be set forth in connection 15 with the drawing.

In the drawing:

Figure 1 is a longitudinal sectional view 20 through a hydrometer embodying this invention.

Fig. 2 is a view in side elevation of the hydrometer.

Fig. 3 is a transverse sectional view on 25 the line 3—3 of Fig. 1.

Fig. 4 shows a slightly modified construction.

In the present instance I have illustrated my invention embodied with a hydrometer 30 structure of the type shown in Patent No. 1,262,478, granted to F. L. Freas, but it is to be understood that this invention is also adaptable to other types of syringe hydrometers.

35 The barrel 1, as illustrated in Figs. 1 to 3, is in the form of a glass tube having beads 2 and 3 around its ends. The extension housing 4 has a spout 5 at one end thereof and a groove 6 is provided at the remaining end to receive the beaded end 3 of the barrel, the extension housing 4 being preferably of less internal diameter than the barrel 1 to provide a shoulder 7 adjacent this beaded end of the barrel.

45 The extension housing is of soft rubber or other non-frangible material which will form a cushion for the frangible barrel 1, and a guard or protective housing 8 is made integral with the extension housing 4 and 50 is adapted to fit around the frangible bar-

rel 1, a syringe bulb 9 being carried at the remaining end of this guard or protective housing 8. The protective housing 8 is cut away at its sides as at 10 and 11 to permit a clear view of the hydrometer float 12, and an annular groove 13 is provided adjacent the syringe bulb 9 to receive the beaded end 2 of the barrel 1.

55 In assembling this structure the barrel 1 is fitted through one of the side openings at 10 or 11, and the guard housing structure is stretched sufficiently to accommodate the length of the barrel 1, the natural resiliency of the material causing the parts to return to a position in which the beaded ends of the barrel 1 are received and are firmly held in the grooves 6 and 13 to establish air and liquid tight connections at these points.

60 A buffer plug 14 is fitted in the end of the barrel 1 adjacent the bulb 9 and is provided with openings, this buffer being adapted to limit movement of the float 12 within the barrel. The hydrometer float 12 has its float 65 end 15 made of a diameter to fit loosely within the extension housing 4, and the gauge stem 16 is of the same or of a reduced diameter. A plurality of guide and centering arms 17 are provided on the upper portion 70 of the float end 15, and these guide arms project radially their extent diametrically being slightly less than the internal diameter of the barrel 1. The guide arms 17 serve to hold and maintain the hydrometer float 12 in a substantially axial position within the barrel 1, and also serve 75 as stops resting upon the cushion flange 7 of the extension housing 4 to maintain the hydrometer float 12 in a position where the passage of the spout 5 is entirely free and open at its inner end, this support upon the shoulder 7 also serving to protect the hydrometer float and afford a cushion to prevent injury of the same due to dropping or other shocks while the instrument is in use.

80 Although I have here shown two openings at 10 and 11, in some adaptations it may be found desirable to provide a single opening, while other constructions may require three 85 or more openings.

90

95

100

In the disclosure in the modified construction as shown in Fig. 4, the guard housing 8' is formed as an integral portion of the extension housing 4' and the syringe bulb 9' is a separate portion. This construction 5 may be found advantageous for use where the upper end of the barrel 1' is reduced in diameter and the bulb 9' is correspondingly reduced. Also, the construction of the parts 10 might be reversed and the guard housing might be formed integral with the syringe bulb and the extension housing or spout might be then made as a separate portion.

While I have shown and described only 15 certain specific embodiments of this invention and have suggested only certain possible modifications, it will be appreciated that this invention is susceptible to a number 20 of adaptations, and that changes and variations can be made in the form, construction and arrangement of the parts without departing from the spirit and scope of my invention.

I claim:

25 1. A syringe hydrometer comprising a frangible barrel, a cushion rubber end portion to receive one end of the barrel and provided with a liquid spout, a second end portion in the form of a syringe bulb to receive the other end of the barrel, and a cushion rubber guard housing intermediate and connected with the end portions and embracing the middle portion of the frangible barrel and provided with an opening 30 through which the barrel is visible.

40 2. A syringe hydrometer comprising a frangible barrel, two end portions of non-frangible cushion material adapted to receive the ends of the barrel, one of said end portions being elongated to form a float housing with a shoulder adjacent the barrel, a hydrometer float movable within the barrel and housing and having portions to engage with the shoulder and afford a cushion 45 support for the float, and a guard housing of non-frangible cushion material around the barrel between the end portions and provided with openings through which the float can be viewed.

50 3. A syringe hydrometer comprising a frangible barrel, a housing of non-frangible cushion material to receive one end of the frangible barrel provided with a liquid spout at its extremity and having a cushion 55 shoulder presented within the end of the barrel, a hydrometer float movable within the barrel and housing and provided with extensions to engage with the shoulder and afford a cushion support for the float, and a guard housing integral with the housing and embracing the body portion of the frangible barrel.

56 4. A syringe hydrometer comprising a frangible barrel, a housing of non-frangible 60 cushion material to receive one end of the

frangible barrel provided with a liquid 70 spout at its extremity and having a cushion shoulder presented within the end of the barrel, a hydrometer float movable within the barrel and housing and provided with extensions to engage with the shoulder and afford a cushion support for the float, a guard 75 housing integral with the housing and embracing the body portion of the frangible barrel, and a syringe bulb integral with the guard housing adapted to receive the remaining end of the frangible housing, said guard housing having an opening through the side thereof through which the frangible barrel is inserted and through which the float can be viewed.

5. A syringe hydrometer comprising a frangible barrel, an end portion of soft rubber to receive one end of the barrel provided with a liquid spout, a syringe bulb of soft rubber adapted to receive the remaining end of the barrel, and a guard housing portion intermediate and integral with the end portion and the syringe to embrace and protect the middle portion of the frangible barrel, said guard housing having an elongated opening therein through which the frangible barrel can be inserted in assembling the hydrometer.

In testimony whereof I hereunto affix my signature.

LEO EDELMANN.
